INVENTOR

UNITED STATES PATENT OFFICE.

AUGUST REININGER, OF SAN FRANCISCO, CALIFORNIA.

FOUNTAIN-BRUSH.

1,182,506.

Specification of Letters Patent.

Patented May 9, 1916.

Application filed May 27, 1915. Serial No. 30,742.

To all whom it may concern:

Be it known that I, AUGUST REININGER, a citizen of the United States, residing at the city and county of San Francisco and State of California, have invented new and useful Improvements in Fountain-Brushes, of which the following is a specification.

This invention relates to fountain brushes and more particularly to devices for applying stenciling liquid or the like, and the object of the invention is to improve the construction and increase the utility and efficiency of the fountain brush.

The invention consists of the parts and the construction and combination of parts as hereinafter more fully described and claimed, having reference to the accompanying drawings, in which—

Figure 1, is a vertical, central section through the brush. Fig. 2, is a cross section on line 2—2, Fig. 1.

The device as a whole consists of a hollow handle 2, on the upper end of which is mounted a removable cap 3. The lower end 25 of the handle is enlarged to form a head 4, and is closed by a bottom section 5. The hollow handle and head form a receptacle for the stenciling ink, or other fluid to be discharged.

30 The brush proper, indicated at 6, is constructed of bristles in the usual manner, which are suitably secured in a head 7. The central portion of the head is threaded as at 8, and is adapted to be screwed on to a 35 threaded projection 9, formed on the bottom section 5 of the head.

The closure or bottom section 5 is provided with a central opening 10, which forms a communication between the fluid receptacle and the bristles of the brush, and this opening or passage is adapted to be opened or closed by a cone-shaped valve 11. This valve is mounted interior of the head and is normally held against its seat by 45 means of a spring 12, which is secured interior of the head by means of a screw cap 13. Formed on one end of the valve and projecting exterior of the head, is a push rod

14; this rod extends through a stuffing box 15 which is provided for the purpose of preventing leakage around the rod 14. The provision of the stuffing box eliminates any leakage around the valve; and a washer 16 interposed between the head and the brush, prevents leakage at that point. 45

In operation, when using the brush, it is only necessary to open the valve by pressing on the outer end of the rod 14. A suitable quantity of the fluid is thus admitted to the bristles of the brush, the valve automatically closing the communicating passage 10, the moment the push rod is released, as the tension of spring 12 will force the valve back against its seat.

A fountain brush constructed as here 65 shown, is simple and substantial in construction and neat in appearance. The exterior parts of the head and handle always remain clean, as the only escape for the fluid is through the central opening 10, which conveys the fluid to the bristles of the brush. 70

The materials and finish of the several parts of the device here shown, are such as the judgment and the experience of the manufacturer may dictate. 75

I wish it understood that various changes in form, proportions and minor details of construction may be resorted to within the scope of the appended claim, and that I do not wish to limit myself to the specific design and construction here shown. 80

Having thus described my invention, what I claim and desire to secure by Letters Patent, is—

In combination with a member having a 85 fluid receiving chamber and a passage leading therefrom, and a pair of interiorly threaded openings extending through opposite sides of said member and connected by a cone-shaped valve seat which latter intersects the passage, a cone-shaped valve in said seat having an enlargement of uniform diameter at one end which enlargement slides in one of said openings and having a reduced push rod passing through the other 90 95 of said openings, a coil spring abutting the

enlargement, a screw cap abutting the spring and closing the opening which receives the spring, stuffing in the other opening, and a gland closing the last named opening and having a central opening receiving the push rod, the latter extending beyond the gland.

5 In testimony whereof I have hereunto set

my hand in the presence of two subscribing witnesses.

AUGUST REININGER.

Witnesses:

JOHN H. HERRING,
W. W. HEALEY.
